24 Claims. (Cl. 230—69)**

The present invention relates to a vacuum means and, 10 more particularly, to a vacuum pump for producing a very high vacuum.

It is frequently desirable to carry on certain types of processes and experiments in an enclosure from which the atmosphere has been removed. Heretofore, the atmosphere has usually been removed by means of a mechanical vacuum pump. Such pumps are ordinarily very effective in removing the atmospheric gases from a container and can produce vacuums of substantial proportions. However, there is naturally a limit to the amount of vacuum which they can effectively create. More particularly, a mechanical pump of high quality may be effective to produce a vacuum on the order of about 10^{-3} millimeters of mercury. As a vacuum approaches this magnitude, the number of gas molecules remaining in the container is relatively small with substantial distances therebetween. In fact there is sufficient space between the molecules to permit electrons to travel through the vacuum with a low probability of collision with any gas molecules. Although a vacuum of the foregoing magnitude is adequate for most vacuum processes, as the accuracy or precision of processes and experiments increase, it has been found that even the small number of molecules present a vacuum on the order of 10^{-3} millimeters of mercury may be sufficient to cause contamination. As a result, it has become increasingly necessary to produce vacuums of even greater magnitude. Heretofore in order to accomplish this, it has been necessary to resort to complex multi-stage mechanical pumps or other complicated, delicate and expensive means that have been somewhat effective to produce greater vacuums. However, such devices and the vacuums they produce are not entirely satisfactory.

It is now proposed to provide a vacuum pump which will overcome the foregoing difficulties. More particularly it is proposed to provide a vacuum pump which is not only simple and reliable in operation, but is also very effective to produce a very high vacuum. This is to be accomplished by providing a first housing that encloses a first region of high vacuum and which is adapted to be interconnected with the container wherein the high vacuum is to be created. In addition, a second housing is provided that encloses a second region of low vacuum and which is adapted to be operatively interconnected with a conventional mechanical vacuum pump. A passage of restricted size is provided between the two regions so that the conventional pump may be effective to remove the atmosphere from the high and low vacuum regions. Electron accelerating means are also provided for directing a stream of free electrons through the first region so as to ionize at least a portion of the gas molecules in the first region. The resultant ionized gas molecules will have an electrical charge that may be attracted by a charge of opposite polarity. Accordingly, an electrode may be disposed adjacent the passage way to produce an electric field that will be effective to attract the ionized gas molecules through the passageway and into

2

the second region where the mechanical pump may remove them. It may thus be seen that a vacuum may be created that is much greater than the vacuum that can be created by a mechanical pump.

5 These and other features and advantages of the present invention will become readily apparent from reading the following detailed description of one embodiment thereof, particularly when read in connection with the accompanying drawings wherein like reference numerals designate like parts and wherein

FIGURE 1 is a transverse cross sectional view of a vacuum pump embodying one form of the present invention; and

15 FIGURE 2 is a perspective view of the vacuum pump of FIGURE 1.

Referring to the drawings in more detail, the present invention is particularly adapted to be embodied in a vacuum pump 10 which may be connected to a container (not shown) in which it is desired to create a vacuum, 20 which is of greater magnitude than can be created by means of a conventional mechanical pump. By way of example, the vacuum may be on the order of 10^{-6} millimeters of mercury, whereas a mechanical pump will ordinarily only produce a vacuum on the order of 10^{-3} millimeters of mercury.

The present pump 10 includes a first housing 12 that includes a header 14 with a conduit 16 projecting from the center thereof. The conduit 16 is adapted to be connected to the container by any suitable means that 30 will permit gas to flow therethrough. The opposite side of the header 14 includes at least one arm that extends therefrom. Although any desired number of arms may be employed, in the present instance, there are two arms 18 and 20 which are substantially parallel to each other.

35 Each of the arms 18 and 20 includes an upper wall 22 and 24 and a lower wall 26 and 28 which are substantially parallel to each other. The walls 22 and 26 and the walls 24 and 28 are separated from each other by a predetermined space. In addition side walls 30 and 32 are secured to the top and bottom walls so as to enclose the spaces therebetween. These spaces communicate with the interior of the header 14 and form first regions 34 and 36 of high vacuum.

A second housing 38 is also provided which includes 45 a top wall 40, a bottom wall 42 and a substantially cylindrical side wall 44. These walls 40, 42 and 44 are all secured together to form an air tight structure which encloses a region 46 of low vacuum. A duct 47 may be provided that communicates with the region 46 and 50 is adapted to be connected to a conventional mechanical vacuum pump (not shown). The side wall 44 includes a pair of openings through which the two arms 18 and 20 may extend. The inner ends of the arms 18 and 20 will thus be disposed inside of the second housing 38 and 55 completely surrounded by the region 46 of low vacuum.

Each of the arms 18 and 20 may include an opening 48 or 50 in the top wall 22 or 24 and the bottom wall 26 and 28 adjacent the inner ends thereof. All of the 60 openings 48, 50, 52 and 54 are preferably coaxial with the axis of the cylindrical wall 44. The openings will thus be disposed in the center of the low vacuum region 46 and in substantial alignment with each other. It may thus be seen that any gas molecules that are present in either region 34 or 46 may flow through any of the 65 openings and into the other region 46 or 34.

Electron accelerating means 56 may be provided for directing a stream of electrons through the vacuum regions

34 and 46. In the present instance, this means includes an electrically conductive cylinder 58 that is mounted between the two arms 18 and 20 so as to be concentric with the cylindrical wall 44. The cylinder 58 will thus be axially aligned with the openings 48 to 54. A conductor 60 may be provided that has one end thereof connected to the cylinder 58. The other end of the conductor 60 extends through an insulator 62 mounted in the side wall 44 and is connected to a coil 63 which is coupled to the output of an oscillator 64. The potential on the cylinder 58 will thus be made to oscillate and produce an electric force field or potential gradient inside of the housing 38.

Since there will be some gas present inside of the housing 38, there will also be some free electrons in the vicinity of the cylinder 58. The field in the cylinder will react with any free electrons and alternately attract and repel them. As a result the electrons will oscillate axially of the cylinder 58. In order to control the direction of these oscillations, a magnetic flux field may be created inside the housing 38. In the present instance, this field is created by a magnetic circuit that comprises a permanent magnet having a core disposed outside of the housing 38. The pole faces 66 and 68 are disposed adjacent and parallel to the end walls 40 and 42. This magnet will thus produce a flux field wherein the lines of flux are substantially parallel to the passageway formed by the openings 48, 50, 52 and 54 and the cylinder 58. Since an electron traveling in a vacuum is constrained to follow magnetic flux lines, any movement of the electrons will be axially of the cylinders 58 and normal to the arms 18 and 20. Accordingly the electrons will travel through the second region 46 and through the pair of first regions 34 and 36 enclosed inside of the arms 18 and 20.

In order to limit the distance that these electrons may travel, a pair of electrodes 70 and 72 may be disposed above and below the arms 18 and 20 and in substantial alignment with the openings 48 to 54. Each of these electrodes 70 and 72 may be connected with a source of negative potential by means of an electrical conductor 74. This source will be effective to maintain the electrodes at a suitable negative potential to produce a strong repulsive force on any of the electrons in the vicinity. As a result after an electron has traveled through the openings 48 or 54 and the regions therebetween, it will be repelled and its excursion terminated. When the polarity of the cylinder 56 again reverses, the electron will travel in the opposite direction axially along the magnetic lines through the arms 18 and 20 so as to be stopped by the opposite electrode.

It may thus be seen that the electrons will oscillate along the magnetic lines of flux and between the two electrodes 70 and 72. In so doing they will travel through the high vacuum regions 34 and 36 inside of the arms 18 and 20. During this portion of their journey, probability of colliding with at least a portion of any gas molecules that are present in the regions 34 and 36. When such a collision occurs at least one electron in the molecular structure will be knocked out of orbit. Thus, after such a collision, there will be two free electrons and one positive ionized gas molecule. The two free electrons will then proceed to oscillate axially of the flux field substantially as described above.

In order to remove the ionized gas molecule, electrodes 75 and 76 may be disposed in the second or low vacuum region 46. Since the ion will possess a positive net charge the electrodes 75 and 76 may be connected to a negative potential on the order of 100 volts by means of a conductor 78. These electrodes 75 and 76 will thus create an electrostatic field which will extend through the openings 50 and 52 and into the first regions 34 and 36. The resultant attractive forces upon the positively charged ions will cause the ions to travel through the openings 50 and 52 towards the electrodes 75 and 76. In addition, the electrodes 70 and 72 will similarly attract positive ions

through the openings 48 and 54. Since the ions will not be constrained to travel along the flux line, they will have a high probability of colliding with the negative electrodes. At the time of such a collision the gas molecules will acquire an electron from the electrodes. The ions then become neutrally charged and are disposed in the second or low vacuum region 46. Since the resultant molecule has no net electric charge of either polarity, it will be free to travel in a random pattern. As a consequence few if any of the molecules will return through the openings 48, 50, 52 and 54. Instead they will tend to remain in the second region 46 whereby the pump will tend to eventually remove the ion from the region 46.

It may thus be seen that in order to employ the present pump 10 for creating a very high vacuum in a container, the conduit 16 extending from the header 14 may be connected to the container whereby the first or high vacuum region inside of the housing 12 may be interconnected with the interior of the container and permit the free flow of gases therebetween. At the same time, the conduit 47 extending from the side of the housing 38 may be connected to a conventional vacuum pump whereby the second or low vacuum region inside of the housing 38 will be interconnected with the pump and permit gas to flow thereto.

Once the pump has been started, it will be effective to remove the gases from the second region 46 enclosed in the housing 38. As this pumping continues, the pressure in the second region 46 will decrease. This in turn will result in the gases in the container and in the first regions 34 and 36 to flow through the openings 48, 50, 52 and 54 and into the second region 46. Eventually, as the pressure approaches the limits of the pump, the pressures in the two regions will become substantially equal. As the vacuums in the two regions 34, 36 and 46 approach the limit of the pump, the various electrodes may all be energized. Since there will still be some gases present in the two regions 34, 36 and 46, there will also be some free electrons present around the electrodes. Thus the oscillations of the potential on the center 58 will cause these electrons to be alternately attracted and repelled. Since the electrons must travel parallel to the direction of the flux field produced by the magnet, they will move axially of the cylindrical electrode 58 and between the electrodes 70 and 72. When the electrons approach the end electrodes 70 and 72, the negative charges on the electrodes 70 and 72 will repel the electrons and thereby provide an effective limit to the amount of axial travel of the electrons. During these oscillations at least a portion of the electrons will travel through the first regions 34 and 36 inside of the arms 18 and 20. A portion of these electrons will collide with a portion of the gas molecules present around the openings 48, 50, 52 and 54. The electrons will have sufficient energy or velocity to cause at least one electron in the molecule to be knocked out of orbit. This will thus produce an ion having a net positive charge and a new free electron. The two electrons will then continue to oscillate axially of the passage substantially as previously described.

The resultant ionized molecule will have a net positive charge and the electric field from the negatively charged electrodes 70, 72, 75 and 76 will attract the positive ion. This will cause the molecule to travel through the openings 48, 50, 52 and 54 and into the region 46 so as to collide with the electrodes 70, 72, 75 and 76. This collision will permit the molecules to thereby acquire a new electron and a neutral net charge. Since the gas molecule will not be subject to any forces from the magnetic field or the electrodes, it will travel in a random manner through the second region 46, although a few of these molecules may tend to travel back through an opening 48, 50, 52 or 54, a large majority of the molecules will tend to remain in the second region 46 whereby they will eventually be removed through the conduit

47 by the mechanical pump. By thus continuously removing at least a portion of the gas molecules present in the ends of the arms 18 and 20, the vacuum in the first region and in the container connected thereto will be increased beyond the capacity of the conventional pump.

It may thus be seen that a new and improved vacuum pump has been provided that will be very effective to produce high vacuums. Although the present invention has been described in relation to one particular embodiment thereof, it will be readily apparent to persons skilled in the art that numerous changes and modifications may be made thereto without departing from the spirit of the invention. Accordingly, the foregoing disclosure is for illustrative purposes only and does not limit the invention which is defined only by the claims which follow.

I claim:

1. In a device for transferring a gas from a region of high vacuum to a region of low vacuum the combination of a passageway extending between said regions, electrode means adjacent said passageway, and means for energizing at least a portion of said electrode means with an alternating voltage to cause free electrons to oscillate axially of said passageway and through said regions, and a collector disposed in the region of low vacuum.

2. In a device for transferring a gas from a first region of high vacuum to a second region of low vacuum the combination of a passageway extending between said regions, electrode means positioned in said device and adjacent said passageway, means for energizing said electrode means with an alternating potential to cause free electrons to oscillate axially of said passageway and through said first region with sufficient velocity to ionize at least a portion of the gas in said first region, and electrode means disposed in said second region adjacent said passageway and having a polarity to attract ions in said first region.

3. Means for transferring at least a portion of the gas present in a first region of high vacuum into a second region of low vacuum, said means comprising the combination of a passageway extending between said regions for interconnecting said regions with each other, electron accelerating means positioned adjacent the passageway for producing a field in the passageway, an alternating power supply interconnected with the electron accelerating means for energizing the electron accelerating means with a radio frequency potential of a sufficient potential for accelerating free electrons through at least said first region with sufficient velocity to ionize at least a portion of any gas present therein, and an ion collector disposed in the region of low vacuum.

4. Means for transferring at least a portion of the gas present in a first region of high vacuum into a second region of low vacuum, said means comprising the combination of a passageway extending between said regions for interconnecting said regions with each other, electron accelerating means positioned adjacent said passageway to create a field in the passageway, an alternating power supply interconnected with the accelerating means for producing an oscillating field in the passageway for causing free electrons to oscillate along paths extending axially through at least the portion of the passageway in said first region with sufficient velocity to ionize at least a portion of said gas therein, and electrode means disposed in said second region adjacent said passageway and spaced from said paths to be separated from electrons being accelerated by said accelerating means, said electrode means having a charge thereon that creates a field that extends along said passageway and into said first region for attracting ionized gas in said first region into said second region.

5. Means for transferring at least a portion of the gas present in a first region of high vacuum to a second region of low vacuum said means comprising the combination of a passageway extending between said regions

for interconnecting said regions with each other so that gas may flow between said regions, magnetic means disposed adjacent to said passageway for creating a flux field with the lines of flux extending axially of said passageway, cold electrode means juxtaposed to said passageway for creating a field therein, and means for energizing said electrode means for causing the free electrons normally present in said passageway to oscillate along said flux lines in spaced relation to said cold electrode means and between said regions with sufficient velocity to ionize at least a portion of the gas in said first region.

6. Means for transferring at least a portion of the gas present in a first region of high vacuum to a second region of low vacuum, said means comprising the combination of a passageway extending between said regions for interconnecting said regions with each other so that gas may flow between said regions, magnetic means disposed for creating a flux field having the lines of flux therein extending axially of said passageway to define a plurality of electron paths, electron accelerating means disposed adjacent said passageway for creating a field within said passageway for accelerating free electrons axially of said passageway along said paths defined by the flux lines, an alternating power supply interconnected with the electron accelerating means for causing the electrons to oscillate along said paths and between said regions with sufficient velocity to cause ionization of at least a portion of said gas in said first region to thereby form a plasma having ionized gas and free electrons, said plasma being electrically non-conductive at the gas pressures present in the first region, and an electrode disposed in said second region and adjacent said passageway, said electrode means having a charge thereon that creates a field that extends along said passageway and into said first region for attracting ionized gas in said first region into said second region.

7. A pump for transferring at least a portion of the gas present in a first region of high vacuum into a second region of low vacuum, said pump comprising the combination of a wall separating said regions from each other, said wall having an opening therein that is effective to permit molecules of said gas to travel between said regions, electron accelerating means disposed adjacent to said opening for creating a field therein, means operatively interconnected with said electrode means for energizing said electrode means to cause free electrons to travel through said openings and between said regions with sufficient velocity to ionize at least a portion of the gas molecule in said first region to thereby form an electrically non-conductive plasma that extends through said opening and between said regions, and an ion collector disposed in the region of low vacuum for collecting the ionized gas molecules.

8. A pump for transferring at least a portion of the gas present in a first region of high vacuum to a second region of low vacuum, said pump comprising the combination of a wall disposed between said region for separating said vacuums from each other, said wall having an opening therein for interconnecting said regions with each other whereby some of the molecules in said vacuums may travel between said regions, magnetic means disposed adjacent said wall for creating a magnetic flux field with the lines of flux extending through said opening and between said regions, center electrodes means disposed adjacent the said wall and substantially aligned with said opening, high frequency means for energizing said electrodes means with an alternating potential for causing free electrons to oscillate along said lines of flux and in said first region with sufficient velocity to cause ionization of at least a portion of the gas molecules in said first region, an end electrode disposed in alignment with one end of the center electrode, and means for applying a potential to said end electrode for repelling the oscillating electrons so as to define the end of their oscillations.

9. A pump for transferring at least a portion of the gas present in a first region of high vacuum into a second region of low vacuum, said pump comprising the combination of a wall disposed between said regions for separating said vacuums from each other, said wall having an opening therein for interconnecting said regions with each other whereby some of the molecules in said vacuums may travel between said regions, means disposed adjacent said wall for creating a magnetic flux field with the lines of flux extending through said opening and between said regions, electrode means disposed adjacent said wall and substantially aligned with said opening, an alternating source operatively interconnected with said electrode means for energizing said electrode means at a high frequency for causing free electrons to oscillate along said lines of flux through said opening and between said regions with sufficient velocity to cause ionization of at least a portion of the gas molecules in said first region, and an electrode disposed in said second region adjacent said opening and having a polarity for attracting the ionized molecules in said first region.

10. A pump for transferring at least a portion of the gas present in a first region of high vacuum to a second region of low vacuum, said pump comprising the combination of a wall disposed between said regions for separating said vacuums from each other, said wall having an opening therein for interconnecting said regions with each other whereby some of the molecules in said vacuums may travel between said regions, a first electrode disposed on one of said wall in substantial alignment with said opening, an additional electrode disposed adjacent said opening for causing free electrons to oscillate through said opening and between said regions in substantial alignment with said electrodes at a sufficient velocity to cause ionization of at least a portion of the gas molecules in said first region, said pair of electrodes having a negative potential for repelling said electrons and limiting the amplitude of their oscillations.

11. A pump for transferring at least a portion of a gas present in a first region of high vacuum to a second region of low vacuum, said pump comprising a wall disposed between said regions for separating said vacuums from each other, said wall having an opening therein for interconnecting said regions with each other whereby some of the molecules in said vacuum may travel between said regions, a first electrode disposed on one side of said wall in substantial alignment with said opening and having a negative potential for repelling said electrons, an additional electrode disposed adjacent said opening for causing a stream of free electrons to oscillate through said opening and into said first region with sufficient velocity to ionize at least a portion of the gas in said first region, and a third electrode disposed in said second region adjacent said opening and having a potential that will attract the ions in said first region.

12. A pump for transferring at least a portion of a gas from a first region of high vacuum to a second region of low vacuum, said pump comprising a wall disposed between said region for separating said vacuum from each other, said wall having an opening therein for interconnecting said regions with each other whereby some of the molecules in said vacuums may travel between said regions, a first electrode disposed on one side of said wall in substantial alignment with said opening, magnetic means positioned to create a flux field with the flux lines extending through said opening, electron accelerating means adjacent said opening and aligned with said flux field for directing a stream of free electrons through said opening and into said first region with sufficient velocity to ionize at least a portion of the gas in said first region, and a third electrode disposed in said second region adjacent said opening and having a charge for attracting the ions from said first region into said second region.

13. A pump for removing at least a portion of the gas in a container enclosing a high vacuum, said pump com-

prising the combination of a housing enclosing a first region of high vacuum and being adapted to be interconnected with said container to form a communication between said vacuums, a second housing enclosing a second region of low vacuum, an opening extending between said regions for interconnecting said regions with each other whereby some of the molecules in said vacuums may travel between said regions, a cylinder disposed relative to said opening for creating a field therein that is effective to accelerate electrons axially thereof and through said first region with a sufficient velocity to ionize at least a portion of the gas in said first region, electrodes disposed adjacent the opposite ends of said opening and having negative charges for limiting the amount of travel of said electrons, and an electrode disposed in said second region adjacent said opening for attracting ions from said first region.

14. The combination of claim 13, including:
a source of high frequency energy interconnected with said cylinder, said source being effective to excite the cylinder at a high frequency whereby the free electrons will oscillate.

15. A pump for removing at least a portion of the gas in a container enclosing a high vacuum, said pump comprising the combination of a housing enclosing a first region of high vacuum and being adapted to be interconnected with said container to form a communication between said vacuums, a second housing enclosing a second region of low vacuum, an opening extending between said regions for interconnecting said regions with each other whereby some of the molecules in said vacuums may travel between said regions, magnetic means positioned to create a magnetic flux field with the lines of flux extending axially of said opening to define electron paths, a cylindrical electrode disposed relative to said opening for creating a field therein that is effective to accelerate free electrons axially of said opening and along the paths and parallel to said lines of flux, said cylindrical electrode being energized to give said electrons a sufficient velocity to ionize at least a portion of the gas in said first region, electrodes positioned adjacent the opposite ends of said opening and in said magnetic field, said electrodes having a negative potential to limit the amount of travel of said electrons, and an additional negatively charged electrode disposed in said second region adjacent said opening and outside of said magnetic field for attracting ions present in said first region.

16. A pump for removing at least a portion of the gas in a container enclosing a high vacuum, said pump comprising the combination of a housing enclosing a first region of high vacuum and being adapted to be interconnected with said container to form a communication between said vacuums, said housing having a pair of substantially parallel arms, a second housing enclosing said arms and forming a second region of low vacuum, at least one opening in each of said arms, said openings being positioned to register with each other and to interconnect said regions with each other whereby gas molecules in said vacuums may travel between said regions, an electrode accelerator disposed between said arms and in substantial alignment with said openings for causing free electrons to oscillate through said openings and between said regions with sufficient velocity to ionize at least a portion of the gas in said arms, and an ion collector disposed in the region of low vacuum for receiving the ions produced by the accelerated free ions.

17. A pump for removing at least a portion of the gas in a container enclosing a high vacuum, said pump comprising the combination of a housing enclosing a first region of high vacuum and being adapted to be interconnected with said container to form a communication between said vacuums, said housing having a pair of substantially parallel arms, a second housing enclosing said arms and forming a second region of low vacuum, at least one opening in each of said arms, said openings being positioned to register with each other and to intercon-

nect said regions with each other whereby gas molecules in said vacuum may travel between said regions, magnetic means disposed on the opposite sides of said arms for creating a flux field that extends through said openings and into said first region, electrode means disposed adjacent said arms and in substantial alignment with said openings for causing free electrons to oscillate along said lines of flux through said openings and between said regions with sufficient velocity to ionize at least a portion of the gas in said arms.,

18. A pump for removing at least a portion of the gas in a container enclosing a high vacuum, said pump comprising the combination of a housing enclosing a first region of high vacuum and being adapted to be interconnected with said container to form a communication between said vacuums, said housing having a pair of substantially parallel arms, a second housing enclosing said arms and a second region of low vacuum, at least one opening in each of said arms, said openings being positioned to register with each other and to interconnect said regions with each other whereby gas molecules in said vacuum may travel between said regions, magnetic means disposed on the opposite sides of said arms for creating a flux field that extends through said openings and into said first region, a cylindrical electrode disposed between said arms and in substantial alignment with said openings, means for energizing said cylindrical electrode to cause free electrons to oscillate along the lines of flux through said openings and said regions with sufficient velocity to ionize at least a portion of the gas in said arms.

19. A pump for removing at least a portion of the gas in a container enclosing a high vacuum, said pump comprising the combination of a housing enclosing a first region of high vacuum and being adapted to be interconnected with said container to form a communication between said vacuums, said housing having a pair of substantially parallel arms, a second housing enclosing said arms and a second region of low vacuum at least one opening in each of said arms said openings being positioned to register with each other and to interconnect said regions with each other whereby gas molecules in said vacuum may travel between said regions, electrode disposed between said arms and in substantial alignment with said openings, means for energizing said cylindrical electrode means to cause free electrons to oscillate along the lines of flux through said openings and between said regions with sufficient velocity to ionize at least a portion of the gas in said arms, and a collector electrode disposed in said first region for collecting said ions.

20. In a device for transferring a gas from a region of high vacuum to a region of low vacuum, the combination of:

a passageway extending between said regions, cold electrode means adjacent said passageway, and power supply means interconnected with said electrode means, said power supply means being effective to energize said electrode means with a sufficient potential to accelerate the free electrons axially of said passageway and through said regions with a sufficient velocity to ionize gas molecules in the passageway.

21. In a device for transferring a gas from a first region of high vacuum to a second region of low vacuum, the combination of:

a passageway extending between said regions, first cold electrode means positioned adjacent said passageway, means for energizing said electrode means with a sufficient potential to cause the free electrons normally present in at least one of said regions to oscillate axially of said passageway and through said first region with sufficient velocity to ionize at least a portion of the gas in said first region, and second cold electrode means disposed in said second region adjacent said passageway and having a polarity to attract ions in said first region.

22. Means for transferring at least a portion of the gas present in a first region of high vacuum into a second region of low vacuum, said means comprising the combination of:

a passageway extending between said regions for interconnecting said regions with each other, electron accelerating means positioned adjacent said passageway and having a potential for accelerating free electrons along a path that extends through at least said first region with sufficient velocity to ionize at least a portion of any gas present therein, magnetic means disposed adjacent the passageway to create magnetic flux lines that extend axially of the passageway so as to make said paths extend axially of the passageway, said electron accelerating means being spaced from the paths of said accelerated electrons so as to prevent collision between the electrons and the accelerating means.

23. Means for transferring at least a portion of the gas present in a first region of high vacuum into a second region of low vacuum, said means comprising the combination of:

a passageway extending between said regions for interconnecting said regions with each other, electron accelerating means positioned adjacent said passageway and having a potential to create a field for accelerating free electrons along a path that extends through at least said first region with sufficient velocity to ionize at least a portion of said gas therein, magnetic means disposed adjacent the passageway to create magnetic flux lines that extend axially of the passageway so as to make said paths extend axially of the passageway, and electrode means disposed in said second region adjacent said passageway, said electrode means having a potential thereon that creates a field in said passageway that repels the free electrons accelerated along the passageway and thereby forms an end to the path at a point that is spaced from the electrode means and attracts the ionized gas.

24. A pump for transferring at least a portion of the gas present in a first region of high vacuum into a second region of low vacuum, said pump comprising the combination of:

a wall disposed between said regions for separating said vacuums from each other, said wall having an opening therein for interconnecting said regions with each other whereby some of the molecules in said vacuums may travel between said regions, a vacuum pump interconnected with one of the first of the regions for removing gas molecules from the region, means disposed adjacent said wall for creating a magnetic flux field with the lines of flux extending through said opening and between said regions to form electron paths, electron accelerating means disposed adjacent said wall and substantially aligned with said opening, a pair of electrode means disposed on the opposite sides of said electron accelerating means and adjacent the ends of said paths, at least one of the electrode means being disposed in the first region, a high frequency power supply interconnected with the electron accelerating means for energizing said accelerating means for causing free electrons to oscillate along the paths defined by the lines of flux and through said opening and between said regions with sufficient velocity to cause ionization of at least a portion of the gas molecules in said first region, and power supply means interconnected with the pair of electrodes for maintaining the electrodes at a potential for repelling the free electrons so as to define the ends of the paths, said power supply means being effective to maintain the electron means in said first

11

region at a potential for attracting the ionized gas molecules in said passageway.
